DESIGN.

J. K. DAVISON.
BADGE.

No. 19,271.

Patented Aug. 20, 1889.

UNITED STATES PATENT OFFICE.

JOSEPH K. DAVISON, OF PHILADELPHIA, PENNSYLVANIA.

DESIGN FOR A BADGE.

SPECIFICATION forming part of Design No. 19,271, dated August 20, 1889.

Application filed June 11, 1889. Serial No. 313,929. Term of patent 14 years.

To all whom it may concern:

Be it known that I, JOSEPH K. DAVISON, a citizen of the United States, residing in the city and county of Philadelphia, State of Pennsylvania, have invented and produced a new and original Design for a Badge, of which the following is a specification, reference being had to the accompanying photograph, forming part thereof.

10 The leading feature of my design for a badge is a cross-shaped figure with scrolls on the limbs thereof.

In the photograph, A designates a cross-

shaped figure, on the ends of which are scrolls B. In the center of the figure is a circular 15 field C, having a cross-bar D thereon.

I claim—

A design for a badge, consisting of a cross-shaped figure with scrolls on the limbs thereof, and a central field with a cross-bar thereon, substantially as shown and described.

JOSEPH K. DAVISON.
